UNITED STATES PATENT OFFICE.

THOMAS L. RIVERS, OF NEWARK, NEW JERSEY.

DESIGN FOR A TRUNK-CATCH.

SPECIFICATION forming part of Design No. 16,871, dated August 24, 1886.

Application filed June 23, 1886. Serial No. 206,054. Term of patent 14 years.

To all whom it may concern:

Be it known that I, THOMAS L. RIVERS, a citizen of the United States, residing at Newark, in the county of Essex and State of New Jersey, have invented and produced a new and original Design for Trunk-Catches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a sectional view of my newly designed trunk-catch, and Fig. 2 is an edge view of the same, these views being deemed necessary to fully illustrate the design.

Heretofore the flanges of the bed-plates of trunk-catches have, when viewed from the front, presented a solid or imperforated face to the eye, the marginal outlines, however, being of a variety of shapes.

The leading feature of the design consists in an open-work trunk-catch flange.

In the drawings, A, A' are respectively the body and cover plates of the catch. b, b are

the raised central parts, around which are the open-work flanges, c, c, which last embrace the more especial features of the invention. Said flanges are in a single plane, and are of an irregular outline, and gradually taper or are contracted at the upper and lower ends of the catch. The perforations f, g, g, h, h, i, i, and j (which do not include the ordinary nail-holes, which are not in themselves novel, except, perhaps, as to their disposition) are of various irregular shapes or configurations, and are disposed successively around the raised central parts.

I claim—

The design for a trunk-catch herein shown and described, the same consisting of a trunk-catch having raised central portions and open-work flange-like portions lying in a single plane therearound.

In testimony that I claim the foregoing I have hereunto set my hand this 21st day of June, 1886.

THOMAS L. RIVERS.
